UNITED STATES PATENT OFFICE.

JOHN H. WILLIAMS, OF COUNCIL GROVE, KANSAS.

HAY-PRESS.

SPECIFICATION forming part of Letters Patent No. 361,912, dated April 26, 1887.

Application filed November 24, 1886. Serial No. 219,811. (No model.)

To all whom it may concern:

Be it known that I, JOHN H. WILLIAMS, a citizen of the United States of America, residing at Council Grove, in the county of Morris 5 and State of Kansas, have invented certain new and useful Improvements in Hay-Presses; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention relates to certain new and useful improvements in baling-presses; and it consists in the construction and combination of the parts, as will be hereinafter fully set forth, and specifically pointed out in the 20 claims.

In the accompanying drawings, which illustrate my invention, Figure 1 is a side elevation of a baling-press embodying my improvements. Fig. 2 is a horizontal section thereof, 25 taken on line $x-x$, Fig. 1. Fig. 3 is a vertical section on line $y-y$, Fig. 2. Fig. 4 is a transverse section on line $z-z$, Fig. 1, looking-toward the front. Fig. 5 is a transverse section on line $w-w$, Fig. 1. Fig. 6 is a detail perspective illustrating the clutches and shifting mechanism. Fig. 7 is a detail perspective of the follower.

A stout frame is provided, consisting of four longitudinal beams, A, braced together at suitable points by cross-beams, as shown. At the forward end of the frame I arrange two parallel beams, $a-a$, their ends being firmly secured to the end brace-beams, A'. Between these parallel beams $a-a$ are secured bearings for the 35 driving-shaft B and reversing-shaft B', and as these shafts are constantly connected by the gear-wheel and pinion $b-b'$, I prefer that these bearings be formed in a single block or casting, a' .

40 The shafts B B' are arranged parallel with each other, their inner ends being mounted in bearings formed in or secured to a cross-beam, A'', just forward of the feeding-chamber C. This feeding-chamber C is closed at the sides and 45 bottom, the top remaining open, except at the rear or discharge end, where a throat-plate, F,

is hinged to the forward end of the upper wall, e, of the baling-chamber E, said plate being held normally in line with said wall e by a spring or springs, f'', secured to the frame. 55 The bottom wall, e', of the baling-chamber is pivoted at its forward or inner end to the frame-beams A of the press, and at the discharge end is connected with adjusting-bolts E', the upper threaded ends of which project 60 through openings in a fixed part of the press, and are fitted with nuts f', by the proper manipulation of which the outer end of wall e' may be raised or lowered to decrease or increase the area of the baling-chamber at the 65 discharge end.

The main or driving shaft B is arranged centrally with respect to the sides of the press-frame, and a beveled pinion, I, is mounted to revolve freely, but not move longitudinally 70 thereon. The hub of this pinion I is provided at one end with a sprocket-wheel, J, and at the other end with a clutch member, k, the teeth of which are inclined and adapted to engage oppositely-inclined teeth formed in the 75 end of a sliding collar, L, splined to said shaft. The reversing-shaft B' is also provided with a loose sprocket-wheel, J', which is connected with the sprocket J on shaft B by a chain, j, and secured rigidly to the hub of this sprocket 80 80 J' is a clutch member, N', the teeth of which are inclined reversely to the teeth on clutch member k, and are arranged to engage with clutch-teeth formed on the end of another sliding collar, N, splined to shaft B'. 85

Spiral or other springs l are arranged to constantly press the clutch members on collars L and N toward their mating clutch members, k and N', and these collars are provided with peripheral grooves l' n'', to engage studs m'', 90 projecting from a large lever, M, at points equidistant from its fulcrum. This lever M is fulcrumed midway between the shafts B and B' on a rigid bracket, M', secured to the frame, and is provided at its inner end with a short 95 rearwardly-extending arm, m, arranged to lie in the path of a stud, O, fixed to the back of the follower D.

Pivoted in ears d', secured to the beams $a-a$, at the front of the frame, are arms H H', carrying at their outer ends sectors provided on their adjacent faces with teeth h h', arranged 100

to mesh with teeth of pinion I; and pivoted to the outer ends of these sectors are connecting-
5 rods G G', the other ends of these connecting-
rods being pivoted in ears d, secured to the back of the follower D. Above and below the sectors, and in a vertical plane with the pinion I, are journaled guide-rolls i i', their journals being arranged in line, respectively, with the pivots of sectors H H', and the smooth
10 outer faces of these sectors travel in contact with these rolls, whereby the toothed inner faces are maintained in mesh with pinion I at the expense of but little friction. The bearings in which the journals of these rollers are
15 mounted may be carried by diagonal or other cross-bars i'', secured to the press-frame.

At the commencement of the operation of baling the parts will be in the position shown in Figs. 2 and 3—that is, the sectors will be
20 at the outermost limit of their motion, the follower withdrawn from the feeding-chamber, and the driving-clutch members k L in engagement. The shaft B, revolving in the direction of the arrow, Figs. 2 and 4, owing to the
25 engagement of the driving-clutch, will actuate pinion I and draw the sectors inward, thus straightening the limbs of the toggles H G and H' G' and moving the follower forward to force hay or other material into the baling-chamber.

30 When the follower reaches its limit of forward movement, the connecting-rod G' will be brought in contact with the arm m of lever M, and shift said lever to disengage the driving-clutch and throw the members N N' of the reversing-clutch into engagement. As the lever or sliding sleeves may become clogged or worn, however, and so fail to act, I have provided lever M with a stud, m', with which the cam-shaped end n' of a spring, n, engages, the
35 arrangement being such that as the stud m' passes the apex of the cam n' the pressure of the spring n will be exerted to complete the shifting movement of the lever in either direction. The reversing-clutch, operating
40 through the sprockets J J' and chain j, will cause the pinion I to rotate in a direction opposite to that of the shaft B, on which it is mounted, and so reverse the movement of the sectors H H' and withdraw the follower to receive another charge of hay. As the follower
45 approaches its limit of withdrawal, the stud O will be brought in contact with the arm m of lever M, and again shift said lever to disengage the members of the reversing-clutch and throw the members of the driving-clutch in
50 engagement to cause the advance of the follower. As the pinion b' is much smaller than the gear-wheel b, which drives it, it follows that while the follower is actuated by the reversing-shaft B' it will move much faster than when impelled forward by the shaft B, thus effecting a great saving of time.

In the operation of such machines difficulty has been experienced from the fact that part
65 of a charge of hay will lodge on the follower and wedge between it and the forward end of the baling-chamber, thus often causing strain

or breakage. By arranging the throat-plate F as shown, hay which may lodge on top of the follower will force the throat-plate F upward, thus relieving the parts from strain, and upon the withdrawal of the plunger the lodged hay will be thrown down into the feeding-chamber C by the action of the springs f'', and be carried forward into the baling-chamber by
75 the next forward movement of the follower.

The degree of compression to which the hay is subjected in the formation of a bale will be regulated by the adjustment of the pivoted bottom e' of the baling-chamber through the
80 adjusting bolts and nuts E' and f'. The driving-shaft B will revolve continuously in one direction, the reversal of the movement of the follower being accomplished automatically by means of lever M and connecting parts, as
85 hereinbefore explained.

I claim—

1. The combination, substantially as described, of the driving and reversing shafts geared together to revolve in opposite directions, and each carrying a loose sprocket-wheel having a clutch member secured to its hub, a pinion secured to the driving-shaft sprocket, a chain connecting the sprockets, the follower, the pivoted toothed sectors and connecting-rods, sliding clutch-collars splined to the driving and reversing shafts, and means controlled by the follower for simultaneously shifting said collars at the end of each stroke.

2. The combination, substantially as described, of the driving and reversing shafts geared together to revolve in opposite directions, and each carrying a loose sprocket-wheel having a clutch member secured to its hub, a pinion secured to the driving-shaft sprocket, a chain for connecting said sprockets, the follower, the pivoted toothed sectors with their connecting-rods, sliding clutch-collars splined on the driving and reversing shafts, a shifting-lever connected to each of said collars, and means connected with the follower for automatically shifting said lever at the end of each stroke.

3. The combination, in a baling-press, of the segmental arms pivotally attached to the frame, said arms being provided with links attached to the follower, and inclined guide-wheels i, substantially as shown, and for the purpose set forth.

4. The combination, with the driving and reversing shafts, their pinions, clutches, and sprockets, the sectors, follower, and connecting-rods, of the shifting-lever connected with the clutch-collars and provided at one end with an arm projecting into the path of both a connecting-rod and the follower, substantially as described.

5. The combination, with the driving and reversing shafts, their pinions, sprockets, and clutches, the follower, sectors, and connecting-rods, of the shifting-lever connected with the clutch-collars and provided at one end with a stud or pin, means controlled by the follower to actuate the lever, and a spring provided

with a cam to engage the stud of the lever, substantially as described.

6. The combination, substantially as described, of the driving-shaft provided with a loose pinion having a sprocket-wheel and clutch member secured to opposite ends of its hub, a sliding clutch-collar splined to said shaft and pressed forward by a spring, the reversing-shaft geared to the driving-shaft and provided with a similarly-arranged clutch-collar, the connected clutch member and sprocket-wheel loosely mounted on the reversing-shaft, a chain connecting the two sprockets, the toothed sectors arranged to engage the loose pinion at opposite sides and pivoted to the

frame, the follower, rods connecting the outer ends of the sectors with the follower, a shifting-lever fulcrumed between and engaging both sliding clutch-collars and arm m and stud m' , carried on opposite ends of said lever, a spring having a cam to engage said stud, and a stud secured to the back of the follower to engage arm m of the lever. 20

In testimony whereof I affix my signature in presence of two witnesses.

JOHN H. WILLIAMS.
